P. BORN, OF SELIN'S GROVE, PENNSYLVANIA.

Design No. 3,758, dated November 23, 1869.

DESIGN FOR A SCHOOL-DESK.

The Schedule referred to in these Letters Patent and making part of the same.

I, P. BORN, of Selin's Grove, in the county of Snyder, and State of Pennsylvania, have invented and produced a new and original Design for School-Desks, of which the following is a specification.

The nature of my design is fully represented in the accompanying drawings, to which reference is made.

It comprehends the desk proper, marked A; the seat, B; partition, C; posts, D; and end piece, E.

The end-piece E is slightly curved, as shown, and the seat-back inclined to the rear.

The drawings exhibit a series of desks and seats arranged on each side of the partition, the seats on

one side of the partition being placed immediately opposite the desks on the other.

I claim, as my invention, the design for school-desks, as shown and described.

In testimony that I claim the above, I have hereunto subscribed my name, in the presence of two witnesses. Selin's Grove, Snyder county, Pennsylvania, April 1, 1869.

P. BORN.
